CLAIM

I claim the ornamental design for a tri-fold display, as shown and described.

DESCRIPTION

FIG. 1 is a front perspective view of a tri-fold display in accordance with the present invention.

FIG. 2 is a front view of the tri-fold display of FIG. 1.

FIG. 3 is a rear view of the tri-fold display of FIG. 1.

FIG. 4 is a top view of the tri-fold display of FIG. 1.

FIG. 5 is a bottom view of the tri-fold display of FIG. 1.

FIG. 6 is a left-side view of the tri-fold display of FIG. 1; and, FIG. 7 is a right-side view of the tri-fold display of FIG. 1.
